UNITED STATES PATENT OFFICE

ERNESTO J. HOYOS, OF BOSTON, MASSACHUSETTS, ASSIGNOR TO HUDSON MOTOR CAR COMPANY, OF DETROIT, MICHIGAN, A CORPORATION OF MICHIGAN

BODY STRIPING

Application filed May 18, 1928. Serial No. 278,810.

This invention relates to a new method and apparatus particularly adapted for the purpose of applying stripes or band designs to automobile bodies. In the manufacture of automobiles it is the practice, after the body has been lacquered or painted, to apply one or more decorative stripes of any desired color combinations to the body along or adjacent the belt line or other moldings, or around the window reveals. In most body plants this work is done by skilled, highly paid specialists or artists who apply the stripes and combinations of stripes by free hand using special brushes. This practice has proved very expensive, since it has added considerably to the cost of production so that efforts have recently been made to devise special devices for painting the stripes on the body, with the view to reducing the cost of the work by enabling cheaper labor to be employed. Such devices however tend to clog and get out of order and are limited in the width of stripe capable of being made. Defective striping is frequent since the evenness and uniformity of the stripe depends largely on the hand and eye of the workman.

Irrespective of whether either of these methods is employed, namely free hand striping or painting the stripe by means of special devices, many objections and disadvantages to this practice are found. For example, where it is desired to apply three stripes including an intermediate stripe of one color and narrower or hair line border stripes of a different color, this must be done in three separate operations. It has been impossible to apply a border line stripe of different color until the paint of the stripe to be bordered has dried. Moreover, since in striping automobile bodies the painting is done on nearly a vertical surface, it has not been found practicable to paint simultaneously two or more contiguous stripes of different colors on account of the paint running together. In making superposed stripes of different colors, one wider than the other, it has been necessary to perform this work in two separate operations, while allowing the paint to dry between operations.

Another disadvantage of present day meth-

ods is that this form of decorative work has been limited to line stripes or continuous color lines, since any other form of decorative band carrying some distinctive or artistic design would require considerable time and great skill, and would therefore be prohibitive under conditions of mass production.

One of the objects of this invention is to overcome the foregoing objections and disadvantages, and to provide a method and apparatus whereby the striping of bodies may be more cheaply and more rapidly accomplished, and as a result of which a wider latitude will be permitted in the character of stripe or band design capable of being applied to the body.

Other objects of this invention will appear in the following description and appended claims, reference being had to the accompanying drawings forming a part of this specification wherein like reference characters designate corresponding parts in the several views.

Fig. 1 is a perspective view of an apparatus embodying my invention and illustrated in position for applying a stripe or band design to an automobile body panel.

Fig. 2 is a central sectional elevation of the construction shown in Fig. 1.

Fig. 3 is a sectional detail view illustrating the manner of mounting the presser rolls.

Figs. 4 and 5 are fragmentary views illustrating a strip or tape carrying a stripe or design and adapted to be applied to the body.

Fig. 6 is a plan view of the construction shown in Fig. 1.

Fig. 7 is a detail sectional view illustrating the manner of supplying fluid to the moistening device.

Fig. 8 is a section taken on line 8—8, Fig. 6, in the direction of the arrows.

Fig. 9 is a detail sectional view illustrating an adjustment of the guide.

Fig. 10 is a fragmentary perspective view showing a somewhat modified form of apparatus for applying the stripe or band design to the convex moulding of a body panel.

Fig. 11 is a detail sectional view illustrating one of the presser rolls of Fig. 10 and associated parts.

Fig. 12 is a plan view of a somewhat modified form of apparatus embodying the invention.

Fig. 13 is a side elevation of the construction shown in Fig. 12.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention beyond the terms of the several claims hereto appended or the requirements of the prior art.

In accordance with the preferred manner of carrying out the invention, the particular stripe or band design, such for example as illustrated in Figs. 4 and 5, which is to be applied to the painted body or body panel is preferably carried on a relatively thin tape or strip which may be wound in a roll or on a reel. The material of the tape or strip is preferably of a cellulose base similar to the lacquer or "duco" employed at the present time for painting automobile bodies or the steel body panels on the interior of pullman cars. Hydro-cellulose may be used and the strip prior to the application of the design thereto is preferably very thin, flexible, transparent or colorless and weatherproof. The design is painted or stencilled on the strip or tape by suitable mechanism, employing preferably a lacquer or "duco" such as used on the body. This design may also be formed in the body of the strip as a homogeneous part thereof. Any design may be produced in this way, and as shown in Figure 4, the margins and intermediate portions of the tape may remain uncolored or transparent, or the entire strip may be painted in suitable designs and color combinations rendering the entire strip opaque, as shown in Fig. 5.

The tape, where wound in a reel, is applied directly to the metal panel of the body by progressively unwinding and treating it so that it will adhere permanently to the surface of the metal body panel. The panel in accordance with present practice is covered with a finishing coating of lacquer or "duco", and the tape may be treated on one face thereof, either as it is applied to the body or just prior thereto, so that when it is progressively pressed onto the body it will fuse, blend or merge with the paint on the body leaving only the design on the strip visible, which would of course ordinarily include a color or colors contrasting with the body colors. In using a strip of cellulose base I prefer to treat it with acetone which has a solvent action on

the strip and body lacquer thereby uniting the two.

In the present instance I have illustrated two methods of treating a waterproof tape of cellulose base. In the first method, as the tape is fed to the body one face of the tape is moistened with a solvent liquid such as acetone, capable of acting on the material sufficiently to partially or slightly dissolve it so that when pressed onto the body it will adhere thereto and fuse or weld with the body paint resulting in melting or merging of the strip and body paint so that the joint is practically invisible. Hence the colored design alone on the tape would be visible on the body. In accordance with the second method the body may be first moistened with the solvent or adhesive fluid along a predetermined line and the strip applied progressively thereto with the result as above described. Where a tape or strip of other material is employed, it may be treated in substantially the same manner with a suitable adhesive fluid or substance and progressively pressed on the body, or a heating element may be employed to act on the tape, so that when pressed on the body it will adhere thereto, and this operation followed up with the application of a coat of transparent duc or lacquer over the tape to render it waterproof.

In the drawings I have illustrated an apparatus by means of which the method of the present invention may be carried out, which is illustrated in connection with the application of the stripe or band design to an automobile body. Figs. 1 to 3 inclusive and 6 to 9 inclusive illustrate the application of the design-carrying tape or band on a line parallel to or spaced from the belt line molding M of the body panel B. Figs. 10 and 11 illustrate the apparatus as modified for the purpose of applying the tape directly to the convex molding M. In these figures the apparatus is constructed so that the strip may be moistened just prior to pressing it along the molding or other predetermined line. Figs. 12 and 13 illustrate a modification in which the strip may be treated to adhere it to the body by first moistening the body, and after applying the tape a follower brush applies a covering coat of transparent "duco" or lacquer.

Referring to Fig. 1 the device includes a frame 20 which may be inexpensively formed as a single casting having a handle 21. The central part of the frame is flat to support the tape roll 22, the tape being wound on a central hollow spool 23 adapted to be slipped over a cylindrical stud 24 and revolve thereon. This stud has a small threaded end 24a screwed into a tapped hole in the frame, and between the shoulder of the stud and the flat face of the frame is clamped a stationary supporting disk 25. After the tape roll is in place an upper disk 26 is fixed on the stud,

this disk having a square center hole fitting over a squared portion 27 on the stud, and the disk 26 is held in position by a knurled nut 28 screwed onto the reduced threaded end 24b of the stud. In this way the roll 22 will revolve, when the strip is unwound, relative to the disks 25 and 26, and the projecting peripheral edges of the disks will position and guide the strip as it comes off the roll, as 10 at the point A in Figs. 1 and 6.

The frame is provided with a bracket 29 at one side of the reel upon which is detachably mounted, by means of set screws 30a and 30b, a reservoir or tank 30 which may 15 contain the moistening fluid or substance. In employing a cellulose strip, I prefer to employ acetone as a moistening fluid which will act on the unpainted face of the strip as a solvent enabling the strip to be pressed 20 on and fused with the body lacquer.

Extending from the tank 30 is a tube 31 having a central duct 32 (see Fig. 7) leading from the reservoir. The flow of fluid is by 25 gravity through the duct and is regulated by a rotatable valve 33 by which the passage may also be closed. The valve is operated by a knurled disk 33a by which it may be turned. The tube 31 leads to an applicator 34, vertically disposed, comprising a chamber screwed 30 onto the end of the tube and carrying a porous applicator pad or sponge 34a.

The tank 30 is mounted to rotate for the purposes of adjustment on the flat ledge 29a of the bracket. The set screw 30a centrally 35 of the tank forms a pivot about which the tank may be turned in order to adjust the position of the pad 34a relative to the strip. The tank is held in adjusted position by means of a set screw 30b extending through 40 the ledge 29a and projecting into an arcuate guide slot 29b concentric with the centre screw 30a.

At the front of the device the frame is provided with a pair of spaced forked brackets 35 and 36 between the forks 35a and 36a of which are revolvably mounted a pair of 45 pressing and applicator rolls 37 and 38 respectively. The leading roll 37 is shown of smaller size than the follower roll 38, and the 50 supporting brackets 35 and 36 are correspondingly of different size, the mounting of the rolls however being preferably identical. Referring to Fig. 3 the forks 36a of the bracket 36 are each slotted at 39 to receive 55 squared slide blocks 40 having a wider flat base 41. Between the parts 41 is located the roll 38 which is carried by a spindle 42 extending freely through holes in the blocks 40 and held in position by cotter pins 43. 60 Springs 44 act against the blocks 40 whereby the roll 38 will yield against the action of these springs. The roll 37 is yieldingly mounted in the same manner as the roll 38, and each roll is preferably composed of relatively soft rubber so as to compress somewhat 65

when pressing the strip against the metal body panel.

The device is provided with guiding means whereby it may be guided in a predetermined path and the strip applied along 70 a predetermined line. In the present instance the guides are especially adapted for cooperation with the molding M, and with this in view I have provided two spaced guides, adjustable into different positions, 75 and adapted to straddle the molding and guide along opposite edges thereof and at longitudinally spaced points.

The frame 20 is provided intermediate the brackets 35 and 36 with a boss 45 (See Figs. 80 1, 2 and 6) having a vertical hole through

which slidingly extends a rod 46 terminating in a square block 47 having a square hole to receive an adjustable squared socket member 48 which is held in adjusted position by

a set screw 49 (Figs. 2 and 6). The member 48 is drilled to receive a slidable guide bar 50 (Figs. 2, 6 and 9) which acts against a compression spring 51 within the opposite

end of the socket member, the guide bar being controlled by a pin and slot connection 52. The guide bar carries at its end a guide 53 comprising an arched rod, terminating in ball tips 53a straddling the molding M. The supporting rod 46 has a vertical groove or

keyway 54 into which projects the end of a set screw 55 by means of which the rod may be held in vertically adjusted position. When applying a stripe below the molding

M as shown in Fig. 9, the guide rod 46 and guide members may be removed, and inverted in the manner shown. The end of the rod is thus insertable through the hole at the top or bottom of the boss 45.

The frame 20 is provided with an extension 56 terminating in a boss 57 through which extends a vertical hole slidingly receiving rod 58 terminating in a square block

59 having a horizontal square hole to receive an adjustable socket member 60 held in adjusted position with respect to the block 59 by a set screw 61. The socket member 60 carries a spring controlled slidable guide bar

62 mounted in the same manner as the guide bar 50. The bar 62 carries at its end an arched rod 63 terminating in this instance in ring tips 64 straddling the molding M. The rod 58 has a vertical groove or keyway 65

into which projects the end of a set screw 66 by means of which the rod may be held in vertically adjusted position. As in the case of the guide 53, the guide 63 and its supporting parts may be inverted when applying a stripe along the underside of the molding M.

The strip S as it passes from the roll 22 is threaded through a guide 67 carried by the bracket 28 and also through a guide 68 carried by the forks 35a and thence passes partly around and underneath the presser roll 37.

The path of the strip S between the loop guides 67 and 68 is such as to carry the bottom face of the strip into contact with the moistening pad 34a, as shown in Figs. 1 and 5 6. The strip also passes between the knives of a cutter or snipping mechanism located preferably directly in advance of the roll 37, which mechanism may be actuated at any time to cut the strip at the completion of a 10 striping operation.

The cutter mechanism comprises a fixed knife 69 secured to the forks 35a (Figs. 6 and 8) and a movable knife 70 adapted to cooperate with the knife 69. Secured to opposite ends of the knife bar 70 are rods or plungers 71 extending freely through holes in U-shaped brackets 72 secured to the opposite faces of the forks 35a. The slide rods 71 carry return springs 73 interposed 15 between the ends of the knife bar and the brackets, and the ends of the rods are upset and secured to angles 74 connected by a vertical rod 75. This rod has a lost motion connection midway its length with the Z-shaped arm 76 of a bell crank lever pivoted at 77 to the underside of the frame. The other arm 78 of the lever has a slotted articulated connection with a link 79 (Figs. 2 and 6). The rear end of this link is pivoted to 20 the upper end of an arm 80 fixed to a rock shaft or spindle 81 to which is pinned a trigger 82 acting against a leaf spring 83. From the foregoing it will be seen that the operator, while grasping the handle 21, can press 25 the trigger 82 resulting in moving the knife 70 against the action of the springs 73 into cooperation with the stationary knife 69 thereby cutting the strip S.

Referring to Figs. 10 and 11, the device 40 illustrated in these views is similar in most respects to the construction described above, with the exception that the rolls 84 and 85 are provided with concave pressing faces adapted to conform to the convex face of the 45 molding M, whereby the strip or tape may be applied directly to the molding. In this instance, the guide socket member 60 is adjustable within a square hole in a block 86 secured to the end of the frame extension 56. This member is held in adjusted position by 50 a set screw 87. In the construction of the front guide, in this embodiment, the frame has an extension 88 drilled to receive the guide bar 50 which slides within the socket member or extension 88 against the action of a spring, as shown in Fig. 11.

In the construction shown in Figs. 12 and 60 13 the strip or tape is treated by applying the moistening material, such as a solvent fluid or adhesive substance, to the body panel in advance of the application of the tape or strip and in the path thereof. After the strip or tape has been applied to the body, it 65 may be covered by a coating of paint or lacquer, this being preferable where it is neces-

sary to protect the strip or tape and render it waterproof or weatherproof. In connection with this form of the invention, the foregoing is accomplished by applying adhesive fluid by means of a leading brush or applicator D to the lacquered or painted body panel, and after the strip is applied, it may be coated with transparent "duco" or lacquer by means of a follower brush or applicator E.

The tank 30 is dispensed with in the construction shown in Figs. 12 and 13 and instead thereof two tanks 89 are provided at opposite sides of the reel or tape roll, each having preferably the same construction. Each tank 89 is mounted in a bracket 91 carried by an extension 90 of the frame. The tank is mounted on top of the bracket to turn on an eccentrically located stud or set screw 92, so that when the tank is revolved about the stud 92 as a centre it will swing toward and from the body panel, thereby providing an adjustment for the applicator D or E. Each tank 89 is held in adjusted position by means of a set screw 94 which extends up through an arcuate slot 93 formed in the top of the bracket 91. The manner of mounting the tank 89 is similar to that shown in connection with the tank 30 with the exception that in this instance the tank revolves about an eccentric axis thereby enabling the applicator D or E to be moved toward or from the body panelling.

Extending from each tank 89 is a tube 95 having a passage therethrough communicating with the interior of the tank or reservoir 89 so that fluid may be fed by gravity through the tube 95 to a brush 97. The flow of fluid may be regulated or shut off by means of a valve controlled by a thumb screw 96, the valve in this instance being identical with the valve 33b in Fig. 7.

With the exception of the foregoing construction, the device in Figs. 12 and 13 is substantially identical with the construction illustrated in Figs. 1 and 6, so that a further detailed description of this apparatus illustrated in Figs. 12 and 13 is not deemed necessary.

When using the device or apparatus illustrated particularly in Figs. 1 and 6, the workman threads the tape or strip S through the guides 67 and 68, and pulls off from the roll a length of tape sufficient to commence the striping operation. The tape end is moistened on the under face thereof and may be pressed by the workman onto the body at the starting point with his finger. With the guides 63 and 50 adjusted and positioned in proper relation to the body, such as in the manner shown in Fig. 1, the workman grasps the handle 21 and moves the device along the body toward the right in Fig. 1. This operation results in drawing the tape or strip S progressively from the roll 22. As the strip passes across the tapered face of the sponge 115 120 125 130

or pad 34a, it is moistened, and is initially applied to the body by means of the spring pressed roll 37. A final pressing operation is accomplished by the follower roll 38. The desired pressure of these rolls is obtained by the operator and this is regulated by the spring mounting of the rolls permitting them to yield and thereby apply the tape or strip in a satisfactory manner. It will be noted that the device in the present instance is guided by means of two spaced sets of guides, each set straddling the convex molding or rib M so that it is impossible for the device to get out of alinement through the carelessness of the workman. When the workman reaches the end of the panel, or line to be striped, he presses the trigger 82 and cuts the strip by means of the cooperating knives 69 and 70. The end of the strip may be pressed onto the body by hand or by moving the device forwardly and pressing it on by the rolls 37 and 38 after the strip has been cut.

The operation of the apparatus illustrated in Figs. 10 and 11 is substantially the same as the foregoing with the exception that the presser rolls 84 and 85 are provided with concave pressing faces adapted to fit over the convex molding or rib M and apply the tape directly to the molding. In this instance the guides are also adjusted to straddle the molding at spaced points longitudinally of the molding thereby insuring proper positioning of the strip or band design as the device is moved over the body.

In the operation of the structure shown in Figs. 12 and 13, the tape or strip is drawn from the roll 22 and applied to the body panel by means of the presser rolls 37 and 38 in the same manner as described above. In this instance, however, the leading brush 97 applies a solvent or adhesive fluid directly to the body panel in advance of the tape and in the path thereof, and in this manner the tape when pressed progressively along the moistened surface will adhere closely to the body. After the tape has been applied by the rolls 37 and 38 a follower brush 97 is adapted to apply a coating of transparent lacquer or "duco" or any other waterproofing material over the tape or strip.

What I claim is:

1. The process of applying a stripe or band design to a painted body which consists in forming a strip of thin cellulose derivative with a predetermined color stripe or design, treating said strip and pressing it against the body to weld the strip and body paint leaving the design or stripe visible on the body.
2. The process of applying a stripe or band design to a body panel or panels having a coating of paint or lacquer, which consists in treating with a solvent one face of a strip of cellulose derivative carrying a visible design on the other face and pressing said strip

against the body to cause a union between the strip and body coating while leaving the design or stripe on the strip visible.

3. The method of forming a stripe or band design on a body having a surface coating of paint or lacquer, which consists in applying to the body a thin flexible strip of soluble transparent cellulose derivative having a visible preformed design, drawing the strip progressively from a source, pressing the strip progressively in a predetermined path against the body, moistening or treating the strip to cause it to unite with the body paint, and applying a transparent coating over the strip.

4. The process of forming a stripe or band design on a body panel or panels having a coating of paint or lacquer, which consists in forming a stripe or design on a flexible transparent strip, applying the strip under pressure to the body while treating one face of the strip with a solvent fluid to cause the strip to unite with the body coating leaving only the stripe or design visible.

5. The method of forming stripes or band designs on the painted surface of an automobile body, which consists in supporting a roll made up of a strip of soluble transparent cellulose derivative carrying a preformed color design, drawing the strip progressively from the roll and applying it progressively to the body while introducing a substance between the strip and body capable of uniting the strip and body paint.

6. The process of forming colored stripes or band designs on the painted surface of an automobile body, which consists in forming a length of a thin normally transparent strip of cellulose derivative with a color design, pressing the strip progressively along the body while introducing between the strip and body a solvent fluid capable of welding the strip and body paint leaving the color design visible.

7. The process of applying a design to a body having a coating of paint, which comprises applying to the body a strip composed of a soluble material having a pre-formed external design, and introducing between the strip and body a fluid capable of substantially dissolving the entire strip into the body paint while leaving the design visible.

8. The process of applying a design to a body having a coating of paint, composed of a cellulose derivative base, which comprises applying to the body a thin sheet also composed of a cellulose derivative base and having a pre-formed external design, and introducing between the sheet and body a solvent fluid capable of substantially dissolving the entire sheet into the body paint while leaving the design visible.

9. The process of applying a design to a body having a coating of paint, composed of a cellulose derivative base, which comprises

applying to the body a thin sheet also composed of a cellulose derivative base and having a pre-formed design, and introducing between the sheet and body a solvent fluid capable of substantially dissolving the entire sheet into the body paint leaving the design visible.

In testimony whereof I affix my signature.
